UNITED STATES PATENT OFFICE.

DWIGHT B. LEE, OF DETROIT, MICHIGAN.

DESIGN FOR A COMBINED AUTOMOBILE BODY AND HOOD.

Application filed April 23, 1927. Serial No. 21,700. Term of patent 14 years.

To all whom it may concern:

Be it known that I, DWIGHT B. LEE, a citizen of the United States, residing at Detroit, County of Wayne, State of Michigan, have invented a certain new, original, and ornamental Design for Combined Automobile Body and Hood, of which the following is a specification, reference being made to the accompanying drawings, forming part thereof.

Figure 1 is a perspective view of a combined automobile body and hood embodying my new design.

Figure 2 is a side elevation of an automobile having a combined body and hood embodying my design, and

Figure 3 is a front elevation of the same.

Figure 4 is a diagrammatic figure showing the outline of the cowl in cross-section, and

Figure 5 is a similar figure indicating the cross-sectional outline of the hood.

A characteristic of my new design is that an approximately vertical ledge is formed on each side of the hood and cowl that forms an extension of the division between the body proper and the lower edges of the windows so that said ledge and dividing line, looking from the side, seem to form a continuum in approximately a single horizontal plane.

To secure the ornamental effect of said design the lower edges of the windows are somewhat higher than usual.

I claim:

The ornamental design for a combined automobile body and hood, as shown and described.

In testimony whereof, I sign the specification.

DWIGHT B. LEE.
